Term of patent 14 years

(Cl. D58—13)

FIG. 1

FIG. 2

FIG. 1 is a perspective view of a compartmented tray showing my new design; and

FIG. 2 is a section taken on the plane of line 2—2 of FIG. 1.

The characteristic feature of my design is appearance of the compartment-forming structure in relation to the inner wall of the peripheral collar of the vertically corrugated tray and the relationship of the upper coplanar edge of the hollow partitions in relation to the low side walls and in which the partition edge is set below the upper edges of the relatively higher end walls, all as shown.

I claim:

The ornamental design for a compartmented tray, as shown and described.
